United States Patent Office

Des. 187,585
Patented Apr. 5, 1960

187,585

BUILDING BLOCK

Raymond W. Clanton, Sunland, Calif., assignor to North Hollywood Concrete Tile Co., North Hollywood, Calif., a copartnership

Application March 19, 1956, Serial No. 40,666

Term of patent 14 years

(Cl. D18—2)

FIG. 1.

FIG. 2.

FIG. 3.

FIG. 4.

FIG. 5.

Fig. 1 is a top view plan of a building block showing my new design;

Fig. 2 is a left side elevational view thereof;

Fig. 3 is a front elevational view thereof;

Fig. 4 is a right side elevational view thereof; and

Fig. 5 is a front perspective view thereof.

I claim:

The ornamental design for a building block, substantially as shown.
